Primary Examiner—Cathron C Brooks

Assistant Examiner—Deanna Fluegeman

(57) CLAIM

The ornamental design for a computer generated image for a display panel or screen, as shown and described.

DESCRIPTION

The single FIGURE is a front view of a computer generated image for a display panel or screen.

The broken lines in the FIGURE are directed to environment and are for illustrative purposes only. The broken lines form no part of the claimed design.

1 Claim, 1 Drawing Sheet
